UNITED STATES PATENT OFFICE.

HENRY B. SARGENT, OF NEW HAVEN, CONNECTICUT, ASSIGNOR TO THE SARGENT & COMPANY, OF SAME PLACE.

DESIGN FOR A LEVER FOR SASH-FASTENERS.

SPECIFICATION forming part of Design No. 32,532, dated April 17, 1900.

Application filed March 22, 1900. Serial No. 9,806. Term of patent 14 years.

To all whom it may concern:

Be it known that I, HENRY B. SARGENT, of the city and county of New Haven, in the State of Connecticut, have invented a new

5 Design for Levers for Sash-Fasteners, of which the following is a full, clear, and exact description when taken in connection with the drawings which form a part thereof, and in which—

10 Figure 1 represents a top view of a lever embodying my design; Fig. 2, a side view, and Fig. 3 a front view.

In all figures similar letters of reference represent like parts.

15 This invention relates to a design for levers for sash-fasteners; and it consists in the configuration hereinafter described and shown in the drawings above referred to.

The lever consists in a substantially semi-20 bowl-shaped plate, with a flat portion A, provided at one end with a vertical thumb-plate

B. A curved and upturned flange C extends along the rear or curved side *a* of the flat portion A from the thumb-plate B to the opposite 25 end *b* of the plate, the upper edge *c* of the flange

being inclined downwardly from substantially the plane of the top of the thumb-plate B to the plane of the flat portion A. Where the upper edge *c* of the flange approaches the plane of the flat portion A a downwardly-inclined channel D extends in the flat portion A adjacent to the flange C and terminates in a concave line *d* in the front side of the flat portion, so that throughout its length the flange forms a distinct feature from the flat 35 portion.

Having now described my design, what I claim, and desire to secure by Letters Patent, is—

The design for a lever for a sash-fastener, 40 as herein shown and described.

In witness whereof I have hereunto set my hand, in the presence of two subscribing witnesses, at New Haven, in the county of New Haven and State of Connecticut, this 20th 45 day of March, 1900.

HENRY B. SARGENT.
